Primary Examiner — Holly Baynham*Assistant Examiner* — Rhea Shields(74) *Attorney, Agent, or Firm* — Womble Carlyle Sandridge & Rice, LLP(57) **CLAIM**

The ornamental design for an article display, as shown and described.

DESCRIPTION

FIG. 1 is a right front perspective view of the article display, showing our new design;

FIG. 2 is a front elevation view thereof;

FIG. 3 is a right elevation view thereof;

FIG. 4 is a left elevation view thereof;

FIG. 5 is a top plan view shown in another environment; and,

FIG. 6 is a bottom plan view.

In the drawings, the broken lines are for the purpose of illustrating environment only and form no part of the claimed design.
